UNITED STATES PATENT OFFICE.

HARRY O. WHITNEY AND CHARLES F. BITZ, OF NEW HAVEN, CONN., ASSIGNEES TO THE WINCHESTER REPEATING ARMS COMPANY, OF SAME PLACE.

MACHINE FOR UNCAPPING CARTRIDGE-SHELLS.

SPECIFICATION forming part of Letters Patent No. 243,022, dated June 14, 1881.

Application filed May 2, 1881. (No model.)

To all whom it may concern:

Be it known that we, HARRY O. WHITNEY and CHARLES F. BITZ, both of New Haven, in the county of New Haven and State of Connecticut, have invented new Improvements in Devices for Removing Primers from Cartridge-Shells; and I do hereby declare the following, when taken in connection with the accompanying drawings and the letters of reference 10 marked thereon, to be a full, clear, and exact description of the same, and which said drawings constitute part of this specification, and represent, in—

Figure 1, a front view of the machine; Fig. 15 2, a vertical central section of the operative parts, enlarged; Fig. 3, a section enlarged to illustrate the operation.

This invention relates to a device for removing primers from cartridge-shells.

20 In the manufacture of cartridge-shells more or less defective primers are inserted in the shells, which, upon inspection, cause the shells to be rejected. From such shells the primers must be removed and perfect primers introduced. Again, shells in large quantities which have been discharged are returned to cartridge-manufacturers from the United States or State governments to be reloaded, and before such reloading can take place the exploded 25 shells, either as to the seat of the primer or the holes in the primer-seat.

Various devices have been resorted to to 30 successfully remove the primers; but in all cases a considerable loss has been experienced from shells damaged in the removal of the primer.

To overcome this difficulty and successfully 35 remove the primer without possible injury to the shell is the object of this invention; and it consists in a tubular spindle arranged to fit closely upon the inside of the primer-seat, combined with a supply of water or its equivalent, and means for forcing the water through 40 a tubular spindle upon the inside of the primer-seat, whence it passes through the perforations in the primer-seat into the primer, communicating the forced pressure to the inside 45 of the primer, which pressure is sufficient to

throw the primer from its seat, whether exploded or not.

The best apparatus for the application of this invention consists of an apparatus something like a power-press, shown in the illustration, in which A A are the two uprights, between which is a vertical slide, B, suitably guided, and to which a reciprocating motion is imparted by a crank or eccentric, C, on the driving-shaft D, and to which power is communicated through a pulley, E, in substantially the usual manner of operating the slide of a power-press.

The instrument applied to the slide and by which the work is performed is shown in vertical section, enlarged, Fig. 2.

a is the spindle, follower, or punch, constructed to enter the cartridge-shell from which the primer is to be removed. Its lower end is constructed with a cavity, b, substantially the shape of the inner side of the primer-seat, and so as to close tightly upon the primer-seat upon the inside of the shell, as seen in Fig. 3. The spindle a is tubular—that is, is hollow, or has an opening, d, through it leading to the 70 primer-seat, and so as to communicate with the perforations through the primer-seat. The spindle a is attached to or made a part of a head or piston, e, arranged to slide within a cylinder, f, the said cylinder forming a water-chamber, g, above the piston, with a valve, h, opening from the water-chamber to the spindle, and also provided with a valve, i, opening from the water-supply tube l into the water-chamber. Each valve is provided with a light 85 spring, which will tend to hold them in their closed positions, and a spring is also arranged in the water-chamber to bear upon the piston, the tendency of which is to force the piston and spindle to which it is attached from the 90 cylinder. This device is applied to the slide B in the usual manner of applying punches and other tools thereto, a flexible or other tube, m, leading water to the water-chamber.

A cartridge-shell in which the primer is 95 fixed is placed in a position directly beneath the spindle. The water-supply has filled the chamber g. The slide B now descends, carrying the spindle a into the shell, and forces it close upon the inner side of the cap-seat, so 100

as to practically make a tight joint between the primer-seat and the end of the spindle. The slide, still descending, carrying with it the cylinder *f*, forces the cylinder down upon 5 the piston, reducing the capacity of the chamber *g*, which causes the water therein to pass down through the spindle to the primer-seat, (the check-valve *i* preventing its return to the source of supply,) and the force of the de- 10 scending cylinder is thus applied to the water, driving it upon the primer with a power sufficient to force the primer from its seat. Then the slide B ascends, the piston returns by the force of the spring in the chamber *g*, the valve 15 *h* closes by the force of its spring, and thus stops the flow of water from the chamber through the spindle, while a fresh supply comes through the valve *i*, to refill the chamber for the next operation. By this application 20 of hydraulic pressure the cartridge-shell is not injured or liable to any of the accidents or injuries to which the ordinary method of removing primers is subject; and as the filling of the water-chamber and the entire operation is 25 automatic, it is performed as quickly and with as great facility as with the usual apparatus.

It will be readily understood that other devices than a power-press may be employed to apply hydraulic pressure. It may be done with 30 a hand-tool, with a lever arranged to force the cylinder upon the piston, or it may simply be done with an apparatus as a hand-tool and a hammer to impart the blow to the cylinder to produce the required hydraulic pressure, wa- 35 ter being supplied to the chamber before the blow is given.

In a power-machine the shells may be presented by the usual dial-feed or other equivalent device, or simply placed by hand in their 40 required position, there being an opening through or in the seat on which the shell stands for the escape of the ejected primer.

While we prefer water or liquid as the means of communicating the force to the primer, it 45 will be readily seen that air may be employed; the chamber *g* being filled with air instead of liquid, the compression of the air in the chamber will operate to eject the primer.

We claim—

50 1. A cartridge-primer ejector consisting of a tubular spindle fitted to close upon the inner

side of the cap-seat in the cartridge-shell, and mechanism, substantially such as described, to produce hydraulic or pneumatic pressure through the said spindle upon the interior of 55 the primer in the primer-seat of the cartridge-shell, substantially as described.

2. The combination of a hollow spindle fitted at one end to close upon the inner side of the primer-seat in a cartridge-shell, its other 60 end arranged to move in a cylinder with a chamber for air or water, and so that the movement of the cylinder, substantially as described, down upon the said spindle will compress the contents of the said chamber and force it there- 65 from through the spindle into the primer, sub- stantially as described.

3. The combination of a hollow spindle con- 70 structed at one end to close upon the inner side of the primer-seat in a cartridge-shell, the other end arranged to move within a cylinder, the said cylinder provided with a supply of air or water, and a check-valve to prevent the return of the air or water from the cylinder to the supply when compression of the cylinder 75 takes place, substantially as described.

4. The combination of a hollow spindle con- 80 structed at one end to close upon the inner side of the primer-seat in a cartridge-shell, the other end arranged to move within a cylinder, the said cylinder provided with a supply of air or water, a check-valve to prevent the return 85 of the air or water from the cylinder to the supply when compression of the cylinder takes place, and a valve-opening from the cylinder to the spindle, substantially as described.

5. The combination of a hollow spindle con- 90 structed at one end to close upon the inner side of the primer-seat in a cartridge-shell, the other end arranged to move within a cylinder, the said cylinder provided with a supply of air or water, a check-valve to prevent the return of the air or water from the cylinder to the supply when compression takes place, and a spring 95 within the cylinder acting upon the spindle to force it from the cylinder after compression takes place, substantially as described.
